US00D814638S

(12) **United States Design Patent** (10) Patent No.: **US D814,638 S**
Lohrenz et al. (45) Date of Patent: ** Apr. 3, 2018

(54) **BRACHYTHERAPY DEVICE**(71) Applicant: **SALUTARIS MEDICAL DEVICES, INC.**, Tucson, AZ (US)(72) Inventors: **Ryan L. Lohrenz**, Vail, AZ (US); **Laurence J. Marsteller**, Tucson, AZ (US); **Tianna D. Benson**, Tucson, AZ (US); **Samuel S. Hyman**, Tucson, AZ (US); **Mary E. Drew**, Oro Valley, AZ (US); **Russell J. Hamilton**, Tucson, AZ (US); **Wendell Lutz**, Tucson, AZ (US)(73) Assignee: **SALUTARIS MEDICAL DEVICES, INC.**, Tucson, AZ (US)(**) Term: **15 Years**(21) Appl. No.: **29/564,247**(22) Filed: **May 11, 2016**(51) LOC (11) Cl. **24-01**

(52) U.S. Cl.

(57) **CLAIM**

The ornamental design for a brachytherapy device, as shown and described.

DESCRIPTION

FIG. 1 is a perspective in-use view of a brachytherapy device showing our new design;

FIG. 2 is a bottom view thereof;

FIG. 3 is a side view thereof;

FIG. 4 is an opposite side view thereof;

FIG. 5 is a top view thereof;

FIG. 6 is a front view thereof; and,

FIG. 7 is a back view thereof.

The broken lines illustrate portions of the brachytherapy device that form no part of the claimed design.
